COMPUTER CONSOLE

William E. Curry, Playa Del Rey, Calif., assignor, by
mesne assignments, to Thompson Ramo Wooldridge
Inc., Cleveland, Ohio, a corporation of Ohio

Application August 19, 1958, Serial No. 52,288

Term of patent 14 years

(Cl. D26—5)

Fig. 1 is a front perspective view of a computer console, showing my new design:

Fig. 2 is a side elevational view, to a reduced scale, the opposite side being substantially a mirror image thereof; and

Fig. 3 is a rear elevational view thereof, to a reduced scale.

The dominant features of the design reside in the portions shown in full lines. The horizontal and vertical broken lines across the upper portion of the console are broken line showings of legible matter for illustrative purposes only.

I claim:

The ornamental design for a computer console, substantially as shown and described.
